(57) **CLAIM**

The ornamental design for a magnetic force attenuator for a cosmetic skin treatment apparatus, as shown and described.

DESCRIPTION

FIG. 1 is a front, left side, and top perspective view of a magnetic force attenuator for a cosmetic skin treatment apparatus showing my new design.

FIG. 2 is a front elevational view thereof.

FIG. 3 is a right side elevational view thereof.

FIG. 4 is a left side elevational view thereof.

FIG. 5 is a top plan view thereof; and,

FIG. 6 is a bottom plan view thereof.

The broken lines illustrate environmental structure that is not part of the claimed design.
